UNITED STATES PATENT OFFICE.

WILLIAM A. KEYS, OF NEW YORK, N. Y., ASSIGNOR TO SLIP SCARF COMPANY, A CORPORATION OF NEW YORK.

NECKWEAR.

1,098,908.

Specification of Letters Patent.

Patented June 2, 1914.

Application filed August 21, 1908. Serial No. 449,606.

REISSUED

To all whom it may concern:

Be it known that I, WILLIAM A. KEYS, a citizen of the United States, and a resident of the city, county, and State of New York, 5 have invented certain new and useful Improvements in Neckwear, of which the following is a specification.

My invention relates to neck-ties, and is adapted for any form of neckwear, either 10 four-in-hand ties, ascots, or what are commonly known as string ties, but it is especially adapted for neckwear to be worn with what are known as two-fold collars, which are in vogue at the present time.

15 As is well known, after an ordinary tie is placed around the neck-band of a two-fold collar between the folds, and the collar then adjusted on the neck of the wearer, it is only with extreme difficulty that the tie 20 can be moved back or forth, the result being that it is almost impossible to properly adjust the tie on the neck of the wearer after the knot has been tied, and it is the overcoming of this difficulty to which my in- 25 vention is addressed.

I have found that by inserting in the neck-band of the tie, in place of the material of the tie itself, a piece of silk, or satin, or some other smooth and thin material, it is 30 possible to make a neck-tie which will move back and forth on two-fold collars very readily, and which will permit the adjustment of the knot after the tie has been tied, without any difficulty.

35 In the drawing forming part hereof, I have shown my invention as applied to a four-in-hand tie.

Figure 1 represents a plan view of a necktie showing my invention, and Fig. 2 a sectional view thereof. Figs. 3 and 4 are, respectively, a plan view and a sectional view of a necktie in which independent interlinings for the tying ends are shown. Fig. 5 is a modification of the tie shown in Figs. 1 45 and 2.

In the drawing A A are the tying ends of the neck-tie.

B is a strip of suitable material like silk or satin, or other relatively anti-friction material, inserted in the neck-band at a point adjacent to the rear of the collar.

E, Fig. 2, is the interlining which extends throughout the tying ends and the neck-band of the tie.

55 In Figs. 1 and 2 the inserted strip of relatively anti-friction material is secured to

the tying ends of the tie by rows of stitching C. It will be noted in the cross-section in Fig. 2 that the tying ends of the tie are relatively thicker than the central part of 60 the neck-band or part adjacent to the rear of the collar. If desired, this central part or bridge piece can be made thinner, as shown in Fig. 5, by having the interlining E substantially thinner at the rear of the 65 collar than it is in the tying ends. If desired, it may be made even thinner by omitting entirely the interlining at the rear of the collar, as shown in Figs. 3 and 4, where, as can be readily seen, the neck-band at the 70 rear of the collar is only about one-third the thickness of the tying ends of the tie. In Figs. 3 and 4 I have shown the strip of relatively anti-friction material inserted on a bias as at F, this being advisable where 75 the neck-tie is cut on a bias.

In the drawing D is a row of stitching which, as shown in Fig. 3, extends lengthwise of the inserted portion B of the neck-band and parallel to the edge of same, and 80 into the portions of the neck-band adjacent to the two ends of the inserted portion B. I have found that rows of stitching running lengthwise of the inserted portion B and extending into the two adjacent ends of the 85 neck-band, strengthen the tie and have a tendency to prevent the same from stretching, particularly where neck-ties are cut on the bias, these rows of stitching I prefer to have meet, as shown in Fig. 1, forming a 90 point at each end of an intermediate portion of the tie, and in this way it penetrates the interlining whether the tie has independent interlinings in the tying ends, or has an interlining thinner in the neckband 95 than in the tying ends, and the interlinings are thereby held in position.

Such modifications and changes as would readily suggest themselves to any one skilled in the art, may be made without departing 100 from the spirit of my invention.

What I claim as new and desire to secure by Letters Patent is:—

1. In a necktie, the combination of a neckband and two tying ends, a portion of 105 said neckband being made of a separate piece of relatively antifriction material and rows of stitching extending lengthwise of the said portion and into the two adjacent parts of the neckband.

2. In a necktie, the combination of a neckband and two tying ends, formed of the 110

- covering fabric and an interlining, an intermediate portion of the tie being made of a separate piece of material, and stitches extending lengthwise along the edges of said 5 intermediate portion and across the tie in a direction oblique to the edges thereof thereby engaging with the interlining to hold the same in position.
3. In a necktie formed of a neckband and 10 two tying ends composed of a two-ply cover fabric and an interlining, an intermediate portion of said cover fabric being made of a separate piece of relatively anti-friction material, rows of stitches passing through 15 the plies of the neckband and said separate piece of material and extending substantially along the edges of said intermediate portion, the said rows of stitches at the end of said intermediate portion passing in 20 a direction oblique to the edges of said intermediate portion and meeting in a point

intermediate the edges of the neckband, the said stitching engaging with and holding the interlining in position.

4. In a necktie having a neckband and 25 two tying ends, an interlining thinner in the neckband than in the tying ends, a two-ply cover fabric, rows of stitching extending lengthwise of the necktie near the edges of an intermediate portion thereof, said 30 rows of stitching passing at the end of said intermediate portion in a direction oblique to the edges of said intermediate portion and engaging with the said interlining to hold same in position.

In testimony whereof, I have signed my name to this specification, in the presence of two subscribing witnesses.

WILLIAM A. KEYS.
